UNITED STATES PATENT OFFICE.

HERMAN STRATER, OF BOSTON, MASSACHUSETTS.

DESIGN FOR A FAUCET-HANDLE.

SPECIFICATION forming part of Design No. 34,864, dated July 30, 1901.

Application filed May 31, 1900. Serial No. 18,675. Term of patent 14 years.

To all whom it may concern:

Be it known that I, HERMAN STRATER, a citizen of the United States, residing at Boston, county of Suffolk, and State of Massachusetts, have invented and produced a new and original Design for a Faucet-Handle, of which the following is a specification, reference being had to the accompanying drawings, forming a part thereof.

Figure 1 of the drawings is a side elevation of a faucet-handle, illustrating my design; and Fig. 2 is a front elevation thereof.

The leading feature of my design for a faucet-handle consists of a spheroidal head surmounting a columnar neck rising from a body having its opposite sides concaved on their outer faces and diverging from the base of the neck to the tops of two depending parallel legs, a downwardly-curved prong being extended from the rear face of the body. A spheroidal or convexed head *a* is shown as

surmounting an elongated columnar neck *b*, erected upon the body portion *c* of the handle, said body portion having opposite sides *c'* concaved on their upper faces and diverging from the base of the neck to the tops of two depending parallel legs *c''*, a downwardly-curved prong *d* extending from the rear face of the body.

Having fully described my design, what I claim, and desire to secure by Letters Patent, is—

The design for a faucet-handle substantially as herein shown and described.

In testimony whereof I have signed my name to this specification in the presence of two subscribing witnesses.

HERMAN STRATER.
